(57) **CLAIM**

The ornamental design for a candle wick trimmer, as shown.

DESCRIPTION

FIG. 1 is perspective view of a candle wick trimmer showing
my new design.

FIG. 2 is a top plan view thereof.

FIG. 3 is a front elevational view thereof.

FIG. 4 is a right side elevational view thereof.

FIG. 5 is a back side elevational view thereof.

FIG. 6 is a left side elevational view thereof.

FIG. 7 is a bottom plan view thereof; and,

FIG. 8 is a perspective view of the candle wick trimmer,
wherein the broken line showing of the jar candle is for
illustrative purposes only and forms no part of the claimed
design.
